UNITED STATES PATENT OFFICE.

VINCENT H. FRANCIS, OF DRUMRIGHT, OKLAHOMA, ASSIGNOR TO FRICK-REID SUPPLY COMPANY, OF PITTSBURGH, PENNSYLVANIA, A CORPORATION OF PENNSYLVANIA.

PUMP.

1,286,272.

Specification of Letters Patent.

Patented Dec. 3, 1918.

Application filed June 23, 1917. Serial No. 176,556.

To all whom it may concern:

Be it known that I, VINCENT H. FRANCIS, a citizen of the United States, and resident of Drumright, in the county of Creek and State of Oklahoma, have invented a new and useful Improvement in Pumps; and I do hereby declare the following to be a full, clear, and exact description thereof.

My invention relates to pumps for oil or like wells, and has particular reference to a type of pump such as described in my application for Letters Patent Serial No. 176,555, filed of even date herewith.

The present invention aims to improve that type of pump by providing a structure which has greater pumping efficiency, and in which the reciprocating pump piston is relieved of the dead weight of the column of fluid in the well tubing.

The invention consists in the novel construction as hereinafter described and claimed.

In the accompanying drawing, Figure 1 is a longitudinal sectional view of my invention, and Fig. 2 is an enlarged sectional view of one of the check valves employed.

The numeral 2 indicates a portion of the well tubing to which my improved pump is attached, the location of the pump with reference to its position in the well being the same as in the standard arrangement for pumping.

The pump comprises the barrel or cylinder 3 which may be the standard working barrel of a regular pumping outfit, having the connections as hereinafter described.

The barrel has the anchor tubing and strainer 4, lower or standing valve 5, and traveling valve or valved piston 6. The piston is adapted for reciprocation by either a wire rope or rod connections to any suitable pumping apparatus.

To connect the piston to the wire rope or pumping rods I employ a tube 7 which is secured to the piston valve 8 and which passes through a stuffing box 9 in the upper end of the working barrel. To the opposite end of this tube is secured a check valve 7^a the purpose of which will herein-after appear, and a valve rod 7^b secured to this valve, as with the common traveling

valve, completes the connection to the pumping cable or rods.

The valved piston of this invention differs from the valved piston or traveling valve commonly employed in oil well pumps, in that the valve crown or casing is not open for fluid communication to the working barrel. Fluid in this instance, which is displaced by the piston on the down stroke, and passing through this valve, enters directly into the tube 7 and is conveyed to the well tubing above the stuffing box. By this arrangement provision is made for displacing fluid through the piston into the well tubing and at the same time by reason of the stuffing box 9 the piston is relieved of the direct overhead load or dead weight of the column of fluid in the well tubing. Also, the arrangement permits of more rapid reciprocation of the piston with less wear of parts, as the tube 7 acts to guide the piston true in the working barrel.

The stuffing box 9 which closes the end of the working barrel forms a chamber 3^a above the piston, and the piston by reason of its incased valve structure, acts in effect, in this chamber, as a solid or non-valved piston, and in its descent creates a suction in this chamber. To utilize this portion of the working barrel for pumping displacement an intake connection with the source of fluid supply is provided.

The intake connection preferably is of a by-pass pipe 10, communicating as at 11 to the chamber 3^a and at 12 with the anchor tubing beneath the strainer openings. A downwardly seating check valve 13 in the by-pass pipe closes communication between the ports 11 and 12 on the up-stroke of the piston. The by-pass preferably is constructed of pipe sections connected by a slip-joint 14, which structure facilitates the assembling of the device.

The enlarged figure of the drawings shows the structure of the by-pass check-valve and slip-joints referred to throughout the description. The valve forms the subject of a separate application for letters patent, and is a form of valve which I prefer to employ, as by its attenuated form

I am enabled to build a very compact structure. I do not however, wish to limit my invention to the employment of any particular form of check-valve in the by-pass lines. Valve 8 of the piston 6 is also of a type similar to the by-pass check valves, and it is obvious that other forms of in-cased check-valves may be used at this point.

A by-pass pipe connection 15 is provided 10 for conveying fluid from the chamber 3^a to the well tubing on the up-stroke of the piston, this connection communicating with the chamber at the port 11, which is at a point above the maximum upper position 15 of the piston, and preferably the pipe is a continuation of the by-pass pipe 10, and terminates in the well tubing above the stuffing box as at 16. This connection is also provided with a downwardly seating check-valve 17 and slip-joint 18.

The above described structure constitutes 20 that portion of my improved pump which is devised to supply fluid to the barrel above the piston for pumping displacement by the piston on its up-stroke.

Both movements of the piston in this invention are utilized for drawing fluid into the barrel and for displacing the fluid. I accomplish this double pumping action by 30 providing means for supplying the barrel above the piston with fluid as above described, and also by providing means for supplying fluid to the barrel beneath the piston simultaneous with the discharge of the 35 fluid from above the piston, the up-stroke of the piston drawing fluid into the barrel through the standing valve 5 as common to all pumps of this general character.

In addition to the intake valve 5, I employ 40 an intake pipe 20, preferably arranged as a by-pass similar in structure and arrangement to the by-pass pipe 10, and having its connection to the anchor tubing at 21 and to the barrel at 22. This pipe also is provided 45 with a downwardly seating check-valve 23 and slip-joint 24. The main purpose of this intake connection is to provide for a greater intake area for fluid being drawn into the barrel on the up-stroke of the piston, and 50 provides means for supplying the barrel with fluid in case of failure of valve 5 and vice versa, the two valves lessening the liability of non-flow due to sand clogging one of these valves. On the down-stroke of the 55 piston fluid drawn into the barrel on the up-stroke is displaced through the valve opening in the piston and is conveyed by tube 7 to the well tubing above the stuffing box. Ordinarily, compression in the barrel be- 60neath the piston does not permit of rapid descent of the piston, the fluid having only a single escape opening, namely, the valve opening of the piston, and in order to provide for a more rapid descent of the piston

I provide an additional outlet for the escape 65 of the fluid, in this instance utilizing the port 22. A pipe 26 having the downwardly seating check-valve 26^a and slip joint 26^b, preferably a continuation of the pipe 20, connects as at 27 to the well tubing above the 70 stuffing box and to the inlet port 22 of the working barrel. Although I have described a preferred form of structure, it will be apparent without specific illustration that various other structural arrangements may be 75 made which function in a similar manner. For instance, each of the by-pass connections may be formed differently, and be so arranged as to have separate port connections with the barrel, and these by-passes 80 may also be formed integrally with the barrel, such as in a casting, without departing from the spirit of my invention.

In the drawings I have shown a check-valve as forming the connection between the 85 valve-rod and tube 7; obviously this connection need not be a valve, as the function of the connection is only to provide communication for the fluid to the well tubing from tube 7, and means for attaching the cable, 90 though by employing a check-valve at this point, there is an advantage, the valve providing additional means to the piston valve in closing communication between the well tubing and the lower chamber of the working barrel, the two valves lessening the liability to leakage due to sand.

In the operation of my improved pump, on the up-stroke of the piston, fluid is drawn 100 into the chamber of the working barrel beneath the piston through standing valve 5 and port 22, and simultaneous with the upward movement, fluid drawn into chamber 3^a by the down-stroke of the piston is forced from this chamber through port 11 and by-pass 15 into the well tubing above the stuffing box. During this movement of the piston, valve 26^a remains closed.

Downward movement of the piston displaces the fluid in the lower chamber of the 110 working barrel, the fluid escaping under pressure of the descending piston through the valve opening of the piston and tube 7, and by port 22 and by-pass 15 to the well tubing. Check-valves 5, 23 and 13 remaining closed during said movement, and check-valve 26^a opening, allowing fluid to be drawn 115 into chamber 3^a by suction of the piston.

It will be seen that as the piston is relieved of the direct overhead load of the 120 column of fluid in the well tubing, by employment of the stuffing box 9, the load on the piston is considerably reduced, and corresponds only to the load produced in displacing fluid from chamber 3^a plus the friction of working parts, and pressure in the by-pass 15. By this arrangement the pumping cable and its connections are relieved of 125

the heavy strains of suddenly picking up the load of the column of fluid.

It will also be seen from the foregoing description that I have provided a pump in which fluid is drawn into the working barrel and displaced therefrom simultaneously by the piston in either direction of its movement, as distinguished from my former application. The structure provides for greater volume of flow per pumping hour, and may be operated at higher speed than common with pumps of this general character. The structure is simple and may readily be applied to the regular pumping outfits.

15 What I claim is:

1. In a pump for oil or other deep wells, the combination with a pumping barrel, of a single fluid-displacing piston therein, a standing valve for admission of fluid, and auxiliary means for supplying the barrel with fluid from the source of supply simultaneously with pumping displacement of the fluid by the piston in either direction of its movement.

25 2. In a pump for oil or other deep wells, the combination with a pumping barrel, of a single fluid-displacing piston therein, a standing valve for admission of fluid, and auxiliary means for supplying the barrel with fluid from the source of supply simultaneously with pumping displacement of the fluid by the piston in either direction of its movement, controlled by the movement of the piston.

35 3. In a pump for oil or other deep wells, the combination with a pumping barrel, of a single fluid-displacing piston therein, a standing valve in the lower end of the barrel for admission of fluid, and auxiliary means for supplying the barrel with fluid from the source of supply alternately to opposite sides of the piston.

45 4. In a pump for oil or other deep wells, the combination with a pumping barrel, of a single fluid-displacing piston therein, a standing valve in the lower end of the barrel for admission of fluid, and auxiliary means for supplying the barrel with fluid from the source of supply alternately to opposite sides of the piston, simultaneously with displacement of the fluid from the barrel by the piston.

55 5. In a pump for oil or other deep wells, the combination with a pumping barrel having a single fluid-displacing piston and including a standing valve for admission of fluid, of a plurality of auxiliary intakes for supplying fluid to the barrel from the source of supply for pumping displacement from the barrel by the piston in either direction of its movement.

60 6. In a pump for oil or other deep wells, the combination with a pumping barrel having a single fluid-displacing piston and includ-

ing a standing valve for admission of fluid, 65 of a plurality of auxiliary intakes for supplying fluid to the barrel from the source of supply simultaneously with displacement of fluid from the barrel by the piston controlled by the movement of the piston. 70

7. A pump for oil or other deep wells comprising a working barrel having a standing valve in the lower end thereof for admission of fluid, a stuffing-box in the upper end of the barrel, a single piston in the barrel, a piston rod connected to said piston and operable through said stuffing-box, a plurality of auxiliary fluid intakes from the source of supply to the barrel above and beneath the piston, and means for bypassing fluid from above and beneath the piston around the stuffing-box to the well tubing. 75

8. A pump for oil or other deep wells comprising a working-barrel having a standing valve in the lower end thereof for admission of fluid, a stuffing-box in the upper end of the barrel, a single piston in the barrel, a piston-rod connected to said piston and operable through said stuffing-box, and an auxiliary intake for fluid comprising a 80 passage having independent communication with the source of fluid supply and terminating in the well tubing above the stuffing-box and having a port communicating with the barrel between the piston and the standing valve adapted for admission and for exhaust of fluid alternately to and from the barrel. 85

9. A pump for oil or other deep wells comprising a working-barrel having a standing valve in the lower end thereof for admission of fluid, a stuffing-box in the upper end of the barrel, a single piston in the barrel, a piston-rod connected to said piston and operable through said stuffing-box, an auxiliary intake for fluid comprising a 90 passage having independent communication with the source of fluid supply and terminating in the well-tubing above the stuffing-box and communicating with the barrel between the piston and the standing valve and adapted for admission and for exhaust of fluid alternately to and from the barrel, and a second like auxiliary fluid passage having a port for admission of fluid to and for 95 exhaust of fluid from the barrel at a point between the piston and the stuffing-box. 100

10. A pump for oil or other deep wells comprising a working-barrel having a standing-valve in the lower end thereof for admission of fluid, a stuffing-box in the upper end of the barrel, a single piston in the barrel, a piston-rod connected to said piston and operable through said stuffing-box, an auxiliary intake for fluid comprising a 105 passage having independent communication with the source of fluid supply and terminating in the well-tubing above the stuffing-box 110

115

120

125

and having a port communicating with the barrel between the piston and the standing valve adapted for admission and for exhaust of fluid alternately to and from the barrel, a second like auxiliary fluid passage having a port for admission of fluid to and for exhaust of fluid from the barrel at a point between the piston and the stuffing-box, and means interiorly of the barrel for

conveying a portion of the fluid from the barrel beneath the piston to the well-tubing above the stuffing-box.

In testimony whereof, I the said VINCENT H. FRANCIS, have hereunto set my hand.

VINCENT H. FRANCIS.
